UNITED STATES PATENT OFFICE.

HENRY ROBERTS, OF PITTSBURG, PENNSYLVANIA.

ROD-COILING APPARATUS.

SPECIFICATION forming part of Letters Patent No. 444,653, dated January 13, 1891.

Application filed October 6, 1890. Serial No. 367,190. (No model.)

To all whom it may concern:

Be it known that I, HENRY ROBERTS, of Pittsburg, in the county of Allegheny and State of Pennsylvania, have invented a new 5 and useful Improvement in Rod-Coiling Apparatus, of which the following is a full, clear, and exact description, reference being had to the accompanying drawings, forming part of this specification, in which—

10 Figure 1 is a sectional side elevation showing my improved coiling apparatus, together with means for carrying away the coiled rods. Fig. 2 is a plan view thereof. Fig. 3 is a vertical cross-section, on an enlarged scale, on the line III III of Fig. 1. Fig. 4 is a side elevation of the coiler, partly in vertical section. Fig. 5 is an enlarged cross-sectional view on the line V V of Fig. 4. Fig. 6 is a view similar to Fig. 4, showing a useful attachment to the coiler to prevent the wear ordinarily occasioned by the rod. Fig. 7 is an enlarged cross-section on the line VII VII of Fig. 6.

Like symbols of reference indicate like parts in each.

25 In rod-mill practice in which the finished rod is received from the rolls by a rotating coiler and delivered in a coil the removal of the hot coils has been attended with considerable labor and expense.

30 One object of my invention is to save this, and thus to lessen the cost of manufacture of the rods.

The second object of the invention is to prevent wear on the end of the coiler and to 35 provide means by which the last end of the rod can be wrapped with greater certainty around a drum or spool which serves to draw it from the coiler.

Referring to the figures on Sheet 1 of the 40 drawings, 22 represents a series of rotating coilers, which may be constructed as shown in my prior patent, No. 426,067, dated April 22, 1890, and each of which is adapted to receive the rod from the rolls and by rotation 45 to deliver it in a coil upon a receiving table or floor. I shall describe their construction more in detail hereinafter with reference to the figures on the second sheet of the drawings. Near the coiler is a covered way 3, 50 which leads to the place in the mill where it is desired to receive the coils for use or for

preparation for shipment. The surface of this way is preferably formed with parallel ribs 1, and may incline upwardly to a downwardly-inclined chute 4.

55

5 6 are sprocket-wheels journaled in the way 3, one of them being provided with suitable driving-gear 7.

8 is a sprocket-chain extending around these wheels in a vertical plane and provided 60 at intervals with outwardly-projecting rods or spurs 10, which are fixed to the chain-links, as shown in Fig. 3, and which in the upper branch of the chain pass through a slot in the cover of the way 3. At or above this slot is 65 a track composed of upright parallel rails or flanges 15, and the spurs are made of sufficient length to extend above the same.

9 are rollers by which the upper branch 70 of the chain is supported.

In using the apparatus the operator, who stands at the coiler or coilers, takes the rod-coil with a hook or other instrument and places it on the rails 15 over one of the passing spurs 10; or the same end may be attained 75 by placing it just over the rear of the sprocket-wheel 5, so that the next spur in rising through the slot will enter the coil. The coil, then resting in an inclined position on the rails and on the ribs 1, is pulled along the same 80 until it reaches the chute 4, where, being released from the spur by the downward passage of the latter over the sprocket-wheel 6, it descends the chute to the mill-floor.

A material advantage is gained by the use 85 of the rails 15, since the coil is supported thereby in an inclined position and is carried by the spur without such disarranging or tangling as would be apt to occur were the coil dragged on its sides along a flat surface. 90

The great saving of labor and the facility of operation afforded by my improved conveying device will be appreciated by those skilled in the art and familiar with the difficult labor heretofore required to remove the 95 coils from the sub floor or cellar in which they are deposited by the coiler. The length of the sprocket-chain may be as great as desired, and the coils therefore may be carried to any convenient part of the rod-mill.

100 I shall now describe the construction of my improved coiler, which is illustrated in detail

in Figs. 4, 5, 6, and 7. The coiler may consist of two concentric cones *b c*, connected by an intervening rib or ribs 11, the outer cone being open at the top, so that it may receive the 5 rod as it is delivered from the rolls. The coiler is supported in a suitable housing, (not shown,) and is rotated on its vertical axis by proper gearing. The rod is delivered from the rolls to and through the space between 10 the cones, through which it travels in contact with the rib 11, and is distributed in a coil upon a floor or platform 12. In order that the last end of the rod may be delivered from the cone when the rod has lost its propulsive 15 power by having passed through the rolls, I employ a drum 13, which is adapted to be raised within the circle described by the delivery end of the coiler. So long as the rod is propelled by the rolls it is distributed in a 20 loose coil; but when it has passed the rolls the rotation of the coiler wraps it around the drum, and such wrapping by exerting tension on the rod draws its end from the coiler. If in order to effect this result the drum were 25 raised within the limits of rotation of the coiler proper, although this could be done, difficulty would be experienced in causing the drum to enter the cone without making it of unduly small diameter, and if the drum 30 should not enter well within the limits of the coiler there would be a space in which the rod would be apt to be snarled. To prevent this I employ a lip or projection 14, which extends down from the rib 11 below the base of the 35 cone for a considerable distance. After passing below the cone the rod is guided by contact with this projection, and if the drum be raised so as to be well within the limits of the circle described by rotation of the projection 40 the wrapping of the rod and drawing out of its last end will be effected without difficulty. As this projection is apt to wear by friction of the rod, I may make it of a separate piece, which is detachably set in position, as shown 45 in Figs. 4 and 5, and when worn can be removed and replaced by another. This is of advantage even when the lip does not extend below the end of the coiler, since the wear at the delivery end of present coilers, which 50 rapidly spoils their utility, can be prevented by inserting a removable piece against which the passing rod has a bearing. In order, how-

ever, to prevent wear of the parts as much as possible, I prefer to employ an anti-friction roller 16, Figs. 6 and 7, which is journaled at 55 the rib at the lower end of the coiler. The rod passes in contact with this roller, which reduces the friction, and thus saves largely the abrasion which otherwise occurs with considerable rapidity. The removable wear-piece or the anti-friction roller may be applied with benefit to tubular coilers or rotating coilers of various patterns.

Without limiting myself strictly to the described form of the coiler, which may be varied in divers ways within the scope of my invention, I claim—

1. In rod-coiling apparatus, the combination, with a rotatory coiling-cone having a downwardly-extending distributing-rib, of a lip set 70 removably in a recess at the end of said rib and projecting below the same, and a drum which is vertically movable within the limit of rotation of the lip to cause removal of the last end of the rod, substantially as and for 75 the purposes described.

2. In a rod-coiler, the combination, with a rotatory coiling-channel through which the rod passes and by which it is delivered in a coil, 80 of a roller situate at the delivery end of the channel, substantially as and for the purposes described.

3. In apparatus for conveying coiled rods from a rod-coiler, the combination of a track or way, adjacent elevated rails 15, on which 85 the coils may ride in an inclined position, said rails having an intermediate slot, and an endless chain having spurs projecting between the rails, substantially as and for the purposes described.

4. In apparatus for conveying coiled rods from a rod-coiler, the combination of a track or way on which the coils may ride, an endless connecting-chain having spurs for engaging and conveying the coils, driving-wheels 95 for the chain, and a downwardly-inclined chute at the final driving-wheel, substantially as and for the purposes described.

In testimony whereof I have hereunto set my hand this 3d day of October, A. D. 1890.

HENRY ROBERTS.
